UNITED STATES PATENT OFFICE.

JAMES H. HURLBUT AND GEORGE W. BEAN, OF PHILADELPHIA, PA.

DESIGN FOR A BOTTLE-HOLDER.

SPECIFICATION forming part of Design No. 17,171, dated March 8, 1887.

Application filed September 30, 1886. Serial No. 215,014. Term of patent 3½ years.

To all whom it may concern:

Be it known that we, JAMES H. HURLBUT and GEORGE W. BEAN, citizens of the United States, residing at Philadelphia, in the county of Philadelphia and State of Pennsylvania, have invented and produced a new and original Design for Holders for Perfumery-Bottles and other Articles, of which the following is a specification, reference being had to the accompanying drawing, forming part thereof.

The figure of the drawing shows the design in elevation.

The leading feature of our design consists in the representation of a lady's boot, the foxing being plain in imitation of "patent leather," and the upper ornamented in imitation of embossed leather. The boot has a broad base, which serves as a support for the same.

In the drawing, A represents the embossed or ornamented portion of the boot, B the plain or foxed portion, and C the base. The shank has a checkered ground, substantially as shown, and has a band, *a*, in front, and the represen-

tation of a scalloped flap ornamented with a 25 row of buttons at the side.

The upper part of the holder is extended, as shown at D, and this extended portion may be either plain or ornamented in imitation of a stocking.

We claim—

The design for perfumery-bottle holders herein shown and described, the same consisting of the representation of a lady's boot mounted upon a base, and having an extended top to represent a portion of a stocking and a checkered shank, as set forth.

In testimony whereof we affix our signatures in presence of two witnesses.

JAMES H. HURLBUT.
